SHEET METAL TREATING MACHINE

Custis S. Woolford, South Orange, N. J., assignor
to American Can Company, New York, N. Y., a
corporation of New Jersey

Application July 12, 1941, Serial No. 402,225

14 Claims. (Cl. 266—7)

The present invention relates to a machine for treating sheet material and has particular reference to the treatment incident to the preparation of those areas of metallic sheet surfaces which ultimately are joined or seamed by soldering or welding.

In can manufacture, sheets or strips of steel or iron, usually referred to as black plate, are coated with tin to produce the well known commercial tinplate. Blanks cut from tinplate are formed into cylindrical shape, and the edges of each blank are joined in a side seam to produce a tubular can body. Such a side seam may be made by the overlapping or interfolding of the blank edges and the firm bonding of the engaging edges by soldering or welding.

In the packaging of some products, it has been suggested that cans manufactured from untinned black plate be used, but difficulty has been encountered in the soldering or welding of the side seams of black plate cans. This is due to the presence of oxide on the black plate, along the areas to be bonded. The same difficulty arises in the use of metallic sheets other than those mentioned. The oxide on the surfaces of these sheets being the source of the difficulty, preparation for soldering, welding and the like may be effected by deoxidizing all or preferably the side seam areas of the sheet surfaces.

The present invention provides a solution to this problem in a machine for removing oxide from predetermined areas of the sheets by treatment with a deoxidizing medium so that those areas subsequently entering into seams or joints may be efficiently soldered or welded.

An object of the invention is the provision of a machine wherein a liquid deoxidant may be applied to the sheets or blanks to remove the oxide from predetermined areas in preparation for their manufacture into cans or the like.

Another object is the provision of a machine of this character wherein the liquid deoxidant may be heated and applied in a smooth flowing stream to predetermined portions of each sheet so that subsequently, these portions may be efficiently soldered or welded together to produce a tight seam or joint adequate to withstand strains such as those produced in hermetically sealed containers.

Another object is the provision of such a machine wherein the sheets are immediately washed with heated water after deoxidation, to remove any excess of the deoxidizing agent and otherwise cleanse the sheets.

Another object of the invention is the provision of means for closely adjusting the deoxidant and water spraying means to the most advantageous and efficient positions with respect to the sheets to be treated.

Another object of the invention is to increase

the efficiency of the deoxidizing and cleansing operations by maintaining the deoxidant and the water at uniform elevated temperatures by thermostatic controls.

5 Another object of the invention is the provision in a machine of this nature, of means for removing drops or globules of free moisture from the sheets after the washing operation, then thoroughly drying the sheets to remove, by evaporation, any moisture remaining upon the sheets.

10 A further object of the invention is the provision of means in such a machine whereby the sheets are moved continuously through the several stages of treatment.

15 Numerous other objects and advantages of the invention will be apparent as it is better understood from the following description, which, taken in connection with the accompanying drawings, discloses a preferred embodiment thereof.

20 Referring to the drawings:

Figure 1 is a small scale plan view of the machine;

Fig. 2 is a side elevation of the machine on the same scale as Fig. 1;

25 Fig. 3 is an enlarged vertical longitudinal section taken substantially along the line 3—3 in Fig. 1 but including only that part of the machine contained within the dot and dash outline C—E—J—H in Fig. 2;

30 Fig. 4 is a transverse vertical section taken substantially along the line 4—4 in Fig. 3 and showing a chain feed drive at the feed end of the machine;

35 Fig. 5 is an enlarged vertical longitudinal section also taken along the section line 3—3, Fig. 1 and is a continuation of Fig. 3 but including only that part of the machine contained within the dot and dash outline E—F—K—J of Fig. 2;

40 Fig. 6 is an enlarged vertical longitudinal section also taken along the line 3—3 in Fig. 1 but showing only that part of the machine contained within the dot and dash outline A—B—F—D of Fig. 2;

45 Fig. 7 is a continuation of Figs. 5 and 6 being an enlarged vertical longitudinal section taken along the line 3—3 in Fig. 1 but including only that part of the machine contained within the dot and dash outline F—G—L—K of Fig. 2;

50 Fig. 8 is a plan view of the machine at the feed end;

Fig. 9 is a transverse vertical section taken through a side guide adjustment mechanism as viewed along the line 9—9 in Fig. 8;

55 Fig. 10 is a plan view at the discharge end of the machine;

Fig. 11 is a transverse section through the machine being indicated by the straight and broken lines 11—11 in Fig. 6;

60 Fig. 12 is a fragmentary section taken sub-

stantially along the broken line 12—12 in Fig. 3 and showing the suction feed parts for feeding the body blank;

Fig. 13 is a fragmentary detail taken along the line 13—13 in Fig. 3, showing the crank drive to a reciprocating blank feed;

Fig. 14 is an elevation of the upper part of the discharge end of the machine with parts broken away to more clearly disclose certain details as viewed along the broken line 14—14 in Fig. 10;

Fig. 15 is a wiring diagram of a direct current electrical circuit used in the machine;

Fig. 16 is a wiring diagram of an alternating current electrical circuit;

Fig. 17 is an enlarged section through an acid discharge nozzle as viewed along the line 17—17 in Fig. 5;

Fig. 18 is an enlarged detailed transverse vertical section through a row of water nozzles as taken along the line 18—18 in Fig. 5;

Fig. 19 is a detailed transverse vertical section of a sheet blotting device, taken substantially along the line 19—19 in Fig. 10;

Fig. 20 is a detailed transverse vertical section through an air-blast unit taken along the line 20—20 in Fig. 10; and

Fig. 21 is an enlarged detailed transverse vertical section through a radiant heat dryer or evaporator as taken along the line 21—21 in Fig. 10.

The drawings disclose a preferred embodiment of the invention whereby metallic sheets or can body blanks, indicated by the letter S, are deoxidized, washed and dried in preparation for seaming by a soldering or welding operation. To this end, the sheets are fed, in substantially vertical position, through descending streams of heated deoxidant, such as hydrochloric or sulphuric acid. For deoxidizing side seam areas only, these streams are directed at marginal opposite edges of the blank destined to enter into the seams to be formed. These treated areas are then washed by similar streams of heated water which cleanse the deoxidized areas.

The moisture on the cleansed areas is then removed from the sheets or blanks in several stages. First, while the sheets are moving in vertical position, the larger drops of water drain from them, leaving some water still clinging to the lower edge. This clinging water is then removed by rotating blotters, but globules still remaining on the margins are subsequently removed by air blasts. Finally, the treated areas are subjected to radiant heat rays which evaporate the remainder of the adhering moisture. The dried sheets or blanks are then stacked by discharge mechanism for removal from the machine. However, they could be transferred, by suitable conveying means, immediately to the soldering or welding machine on which the seams are to be made.

These blanks or sheets S are fed singly and in timed order, from a magazine or stack 31 on the entrance or feed end, which is the left end of the machine as viewed in Figs. 2 and 3. The blanks are retained in a substantially vertical stack by supports 32 mounted on a table 33 secured upon a main housing frame 34, which extends substantially the full length of the machine and is supported upon a structural steel base frame 35.

Blanks are removed from the bottom of the stack 31 and are placed upon the table 33 by a suction separator 36 (Figs. 3, 5, 8 and 12) slid-

ably mounted within a bracket 41 adjustably secured to the table 33. The separator comprises a flexible suction cup 42 set into a slide 43 which is vertically reciprocable within the bracket 41 by linkage with an eccentric 44 on a drive shaft 45 connected, through a clutch 46, to a main drive shaft 47 driven, through reduction gearing 48 and a belt drive 49, by a motor 50. The purpose and manner of actuating the clutch 46 will be stated hereinafter in a description of the wiring diagram shown in Fig. 15, the primary clutch actuating means being an electromagnet 51.

Linkage of slide 43 with shaft 45, comprises 15 a pair of levers 56 and 57 keyed to a shaft 58 journaled in bearings 59 formed in the table 33 and a link 61 pivotally connected at one end with eccentric 44 and at the other end with the free extremity of lever 57. Through this linkage, lever 56 is oscillated and its movement is translated into vertical rectilinear motion of the slide 43 through a rack and segment connection 62 between lever 56 and slide 43.

The cup 42, when at the top of its stroke, engages the lowermost blank in the stack and is in communication through suitable channels, pipes, and valves with a vacuum pump, or other vacuum source not shown. A suction grip is thus maintained as the blank is withdrawn from the stack 20 and is placed upon the table on the downward stroke of the cup. Simultaneously, communication with the vacuum source is disconnected by a control valve 65 located in the vacuum line and actuated through a bell crank 66, a link rod 67 and a lever 68 which is keyed to the shaft 58. Soon after the vacuum communication is thus cut off, the blank has reached the table and suction in the cup 42 is broken by actuation of a 30 vent valve 71 arranged in the line as through a lever 72 keyed to the shaft 58. Suction control is thus synchronized with the vertical movements of the cup.

Having been thus released from the suction cup 42, the blank is engaged by a pair of dogs 45 55 located on a horizontally reciprocating feed slide 76, whereby the blank is carried forward. Slide 76 (Fig. 9) is mounted in guideways 77 formed in the table 33 and is caused to reciprocate therein by a crank 78 to which it is connected by means of a link 79. (See Figs. 3 and 13.) Crank 78 is keyed to a vertical shaft 81 journaled in a bearing 82 formed in an adjustable slide 83 set in ways 84 cut in the upper portion of a housing 85 mounted upon the base frame 35. Shaft 81 is driven from the horizontal drive shaft 45 through the medium of bevel gears 86 and 87 keyed respectively to the shafts 45 and 81.

A wide range of sheet or blank sizes may be accommodated by this machine, so provision is made for the adjustment of the horizontal feed to insure proper delivery of blanks of a given length. This adjustment is effected by rotation of a threaded shaft 91 which is journaled in a bearing 92 formed in the housing 85 and which is restrained from axial movement by a plate 93 bolted to the housing and by a retaining shoulder 94 of the shaft held within an annular confining groove 95 formed in the outer end of the bearing 92. The inner end of the shaft 91 threadedly engages a lug 96 formed on the under side of the slide 83 so that rotation of the shaft 91 will effect longitudinal adjustment, with respect to the machine, of the slide 83, together

with feed slide 76, above, and bevel gears 86 and 87, below.

As each blank S is advanced over the table 33 by the feed dogs 76 to the full stroke of the crank 78, the blank is attracted toward the table by a series of permanent magnets 101, mounted upon but located beneath the plane of the table surface, whereby the frictional engagement between blank and table is increased and the blank is maintained in the position to which it has been advanced. Other auxiliary feed dogs 102 of well known construction in sheet feeding mechanism, are spring pressed or yieldingly mounted upon the feed slide 76 in advance of dogs 76 by substantially the length of the feed stroke, and these dogs 102, by virtue of their spring pressed mounting, are depressed and pass back, under the blank fed by dogs 76, on the return stroke of slide 76. The blank next is advanced by the dogs 102 and subsequently is advanced further in its step by step movement at each stroke of the slide, by other dogs 102 in advance and likewise mounted and spaced upon the slide 76 until the blank reaches the end of table 33.

While being thus advanced over table 33, the blanks are restrained from excessive lateral movement by adjustable lateral guides 105 slidably mounted on table 33 (Figs. 8 and 9). To accommodate a particular width of blank, these guides may be moved laterally of the direction of blank movement, without disturbing their parallel relationship to each other and to the path of sheet travel. This movement of one or the other of the guides 105 may be effected by applying a suitable wrench or other tool on a square end 106 of either of two screw shafts 107 associated with each guide 105. Turning of the screw shaft the requisite amount in the proper direction provides the required adjustment.

The shafts 107 are journaled in bearings 108 formed in the under side of the table 33, each shaft being held against axial movement by a collar 109 pinned to the shaft on one side and a sprocket 111 pinned on the shaft on the other side of the bearing 108. A sprocket chain 112 engages each pair of sprockets associated with each particular guide so that when one shaft 105 is turned, the other is rotated a like amount in the same direction. The inner end 113 of each shaft 107 is in threaded engagement with a downwardly projecting lug 114, secured to the guide 105 there being two lugs for the two shafts associated with each guide. The requisite amount of adjustment desired is thus obtained by the simultaneous rotation of the two shafts 107 associated therewith.

At the end of the last forward advance given a blank by the feed slide 76, the forward edge of the blank is engaged and stopped by a cushioning device 121, shown in Figs. 3 and 8, mounted at the end of table 33. As the slide recedes, the blank is then picked up by a pair of prongs 122 secured to conveyor chains 123 which take over a pair of sprockets 124 (Fig. 3) at the feed end and which also take over a like pair of sprockets 125 (Figs. 5 and 10) at the discharge end of the conveyor, all of which sprockets are positively driven to avoid creating unnecessary tension in the links of the chain.

This positive drive is effected with power derived from the main drive shaft 47, through a bevel gear drive 126 associated with the drive shaft 47 at the discharge end of the machine and located within a main drive housing 127 (Fig. 5) secured to the base frame 35. The drive 126

units the drive shaft 47 with an intermediate shaft 128 extending at right angles to the drive shaft, being journaled at its lower extremity in a bearing 129 formed in the drive housing 127. The upper extremity of the intermediate shaft 128 is journaled in an upper drive housing 135 wherein another bevel gear drive 136 unites, in driving relationship, the intermediate shaft 128 with a horizontal upper drive shaft 137. Shaft 137 extends through the housing 135 and is journaled in bearings 138 formed in the housing 135 and also is journaled at its extremities, in a bearing 139 (Fig. 5) and in a bearing 140 (Fig. 3). Bearing 139 is formed in a discharge end transmission box 141 and bearing 140 is formed in a feed end transmission box 142, the transmission boxes being mounted upon opposite ends of a reservoir or bath frame 143.

The shaft 137 extending between the transmission boxes 141, 142 drives the sprockets 125 and 124 through suitable gearing. A typical gearing for this purpose will be described in connection with the box 142 shown in Fig. 4. Such a gearing comprises a worm 146 keyed to the inner extremity of shaft 137 which meshes with a worm wheel 147 keyed to an intermediate shaft 148 journaled in the transmission box and having keyed to it a drive gear 149. Drive gear 149 meshes with an idler gear 151 freely mounted on a shaft 152 likewise journaled in the transmission box 142. The idler gear meshes in turn with an upper gear 153 keyed to a sprocket shaft 154 which extends through and is journaled in the transmission box. The shaft 154 outside of the box also is journaled in a bearing 156 formed in a bracket 157 bolted to the end of reservoir frame 143. The two sprockets 124 are keyed to the sprocket shaft 154 on opposite sides of the bearing 156.

In the same manner the sprockets 125 are driven from the shaft 137 where it extends into the transmission box 141. A sprocket shaft 161 journaled in a bearing 162 formed in a bracket 163 secured to the other end of the reservoir frame 143 carries the two sprockets 125 (see also Fig. 10).

The conveyor chains, thus driven by the sprockets 124 and 125, also take over idler sprockets 164 (Fig. 5) located at the discharge end of the machine. These sprockets are keyed to a shaft 165 journaled in the bracket 163. At the feed-in end of the machine (Figs. 3 and 4) tightener sprockets 166 are keyed to a short shaft 167. This shaft is mounted in the upper web of an inverted U-shaped adjustment lever 168 the legs of which carry a pivot shaft 169 mounted on the bracket 157. A set screw carried in the adjustment lever provides for tightening the chains as desired.

As the chains pass over the reservoir frame 143 they are supported on rails 170 secured to the frame. The closely spaced prongs 122 previously mentioned are light in weight and are designed for keeping the blanks in spaced parallel position during treatment in the machine. Thus a single blank S may be supported in proper position while being confined between adjacent prongs on the two chains.

Each blank S picked up by a pair of prongs 122 (Fig. 3) from the feed table 33, while being lifted is rotated radially about the center of the sprocket shaft thus passing from a horizontal to a vertical position while being retained by the closely spaced prongs. After the deoxidizing and washing treatment, the blank reaches the dis-

charge end of the conveyor when it is rotated, while held in radial position about the center of the sprocket shaft 161 (Fig. 5), from a vertical to a horizontal position.

During the time that the blanks are retained in their vertical position on the conveyor, they are confined within a treating chamber 171 contained in suitable housing frames 172 (Figs. 3, 5, 6 and 11) secured upon the main frame 34. The frames 172 confine the reservoir frame 143 which is laterally heat insulated from the frame 172. A ventilating system 173, mounted in the top and communicating with the interior of chamber 171, removes injurious fumes which may be generated within the chamber, such fumes being carried away to some remote point where their injurious effects will be dissipated.

Soon after the blanks enter the treating chamber 171, they are treated from above with a de-oxidizing fluid such as a hydrochloric or sulphuric acid solution, streams of which are directed against the upper lateral edges of the sheets, the liquid flowing down over the marginal strips or edges which constitute the seam areas for soldering or welding.

The deoxidant solution is stored in an acid bath 176 (Fig. 11) formed in the reservoir frame 143, from which it is withdrawn through a conduit 177 by an acid pump unit 178. Such a unit is carried by and is secured to the base frame 35. The liquid from the discharge end of the pump passes upwardly through an ascending conduit 179 to a transverse header 181 from which the solution is distributed through a pair of flexible conduits 182 (see also Fig. 6) to manifolds 183 arranged on both sides of the machine. Each manifold is supported, above the path of the moving blanks, on an adjustable frame work which will be described hereinafter. Acid stream nozzles 185 are threaded into the lower wall of each manifold, from which they extend down in a row to within a short distance of the upper edges of the passing blanks. Each manifold contains two chambers, an acid distributing chamber 186 into which the flexible conduits 182 lead and a water distributing chamber 187.

The deoxidant distributed to the nozzles 185 from the chambers 186, enters each nozzle through a restricted entrance 188 (Fig. 17) of an expanding orifice 189 in which a partial vacuum is created causing a reduced velocity in the flow of the liquid through the adjoining passageway, indicated by the numeral 190. This forms the stream which emerges from the nozzle and which flows upon the predetermined marginal areas at the front and rear of each passing blank. Such streams provide for sufficient and full exposure to the deoxidant, whereby the entire lengths of the margins are treated by the descending deoxidant. Excess of deoxidizing solution passing downwardly between the blanks falls back into the acid bath 176 located directly below.

As the blanks, continuing along their horizontal path of travel, advance beyond the curtains of deoxidant and from the acid bath, they next pass over a water bath 195 (Fig. 5). This bath is located at the discharge end of the reservoir frame 143. The blanks pass under a series of water nozzles 196 (see also Fig. 18) disposed in similar manner to that of the acid nozzles 185. Water is projected upon the same lateral margins of the passing blanks which have been acid treated as just described.

Water supplied to nozzles 196, is stored in the bath 195 from which it is drawn through

5 a conduit 197 by a water pump unit 198 secured to the base frame 35. From the pump discharge end, the water is forced upwardly through an ascending conduit 199 to a transverse water header 201 (Fig. 6) from which the water is distributed through a pair of flexible conduits 202 to the water distributing chambers 187 formed in the manifolds 183. Water nozzles 196 (Fig. 18) are threaded secured to the under 10 sides of the manifolds in communication with the chambers 187 and being formed structurally in substantially the same manner as the acid nozzles also produce curtains of descending water streams through which the blank margins, previously treated with acid, are passed. However, the water curtains preferably are somewhat wider than the acid curtains so that the blank margins will be cleansed thoroughly by the water.

As the blanks pass from the water curtains, water continues to drip from their lower edges into the water bath 195. However some partially formed drops remain clinging to the edges. These drops next are blotted from the edges by absorbent or blotter rolls 205 (Figs. 5, 10, 19) which may be keyed to the sprocket shaft 161. Each blank next is rotated from its vertical position on the conveyor to its horizontal position which brings it to a discharge table 206 (Figs. 5, 7 and 10) fastened to a sub-table 207 supported upon and secured to the main frame 34. The blanks are now ready for subsequent treatment which will be hereinafter described.

Both the deoxidant fluid and the water which are flowed upon the blanks are heated, a temperature suitable for the most effective action of the deoxidant being maintained under automatic control. Heating of the fluid in either the acid or water baths for this purpose is effected by injecting steam, obtained from any suitable source, into the fluid near the bottom of the bath. The heating control systems being substantially alike for both deoxidant and water, a description of the deoxidant control will suffice for both, appropriate references being made to the water systems where necessary.

Steam, from any suitable source, not shown, passes from a pipe 211 (Fig. 3) through a thermostatic control valve 212 and piping 213 to a perforated pipe 214 (see also Fig. 5) located within and near the bottom of the acid bath 176. A similar pipe 214 may extend in the bottom of the water bath 195 and may have its own control valve 212 and pipe connection 213.

The valve 212 is controlled by a thermostatic or heat-sensitive controlling device 215 (Fig. 6) suitably positioned to extend into the acid header 181 and into the water header 201 or in any other position where it will be in intimate contact with the flowing fluid therein. Such temperature control of a liquid is well known and it is believed need not be shown further. It may be said, however, that there is a connection between the thermostatic controlling device 215 and the control valve 212 whereby the valve is kept open and steam is allowed to enter the fluid baths, as long as the fluid flowing through the particular header is below the required temperature at which the control device is set. When the flowing fluid reaches the desired temperature, the steam is shut off until such time as the temperature again falls below that for which the control is set.

Horizontal and vertical adjustment of the acid or water nozzles with respect to the edges of the passing blank, which was briefly suggested,

will now be considered. It is desirable for efficient treatment to have such adjustment by reason of the number of variable factors entering into the production of the most effective treatment. Among these factors may be mentioned, the length of the blanks and the width or height of the blanks.

These adjustments in the present embodiment of the invention may be made by turning, either a horizontal adjustment shaft 221 (Figs. 6 and 11) or a vertical adjustment shaft 222 as required. This may be performed in a simple manner by applying a wrench or other suitable tool adapted to engage the square ends 223, 224 of the respective shafts.

The horizontal adjustment will first be considered. Intermediate its length, horizontal adjustment shaft 221 is journaled and restrained from axial movement, in a bearing block 225 secured intermediately of a transverse rail 226 which is mounted at its extremities on inwardly projecting ledges 227 of the frame 112. Within the bearing block 225, a spiral gear 231 is keyed to the shaft 221 and meshes with a second spiral gear 232 which is keyed to one end of a longitudinally disposed shaft 233 journaled at one end in the block 225 and above shaft 221 and at its remote end, in a second bearing block 234 secured, about midway, to a second transverse rail 235 fixedly mounted on the frame ledges 227. Within the block 234, a spiral gear 236 is keyed to the shaft 233 and meshes with a lower spiral gear 237 keyed to a transverse shaft 241. Shaft 241 is arranged parallel with the adjusting shaft 221 and is journaled in the block 234.

Shaft 221 (Fig. 11) is threaded adjacent its end as at 242 and such threaded end extends to the right of the block 225 threadedly engaging in a longitudinally disposed rail 243 which is slidably supported at its ends on the transverse rails 226, 235. In the same way shaft 241 is threaded adjacent its block 234 and it also has threaded connection in the rail 243.

Similarly, threaded portions 244 of the shafts 221, 241 extend forwardly of the blocks 225, 234 and threadedly engage opposite ends of another longitudinally disposed rail 245, slidably supported at its ends on the transverse rails 226, 235. The threaded portion 244 of the shaft 221 is shown in Fig. 11. The screw threads 242 of both shafts 221 and 241 are left hand, while the threaded portions 244 are right hand. Obviously when horizontal adjustment shaft 221 is rotated and shaft 241 is thereby given like rotation through the above-mentioned gear drives 231, 232 and 236, 237, the longitudinally disposed rails 243, 245 are slid along the transverse rails 226, 235 simultaneously. Such movement may be either toward or away from each other equally on both sides of the centrally mounted bearing blocks 225, 234. Manifolds 183, 184 and their respective acid and water nozzles 185, 196 are carried on vertical guide bars 246 (Fig. 11) which are supported by and suspended from the rails 243, 245. This insures the desired horizontal adjustment for the nozzles by operation of the horizontal adjustment shaft 221.

As to the vertical adjustment for the nozzles 185, 196, vertical guideways or channels 251 (Fig. 11) are formed in each of the manifolds 183, 184. Into these guideways, the vertical guide bars 246 have sliding engagement. A bracket plate 252 is bolted to each manifold and encloses its guide bar. There are four guide bars and four bracket plates 252 and the latter also

provide threaded engagement with four vertically disposed threaded shafts 253, whereby the manifolds are adjustably supported.

The lower end of each shaft 253 is supported upon, and is journaled in an L-shaped bracket 254 which is secured to each guide bar 246 near the lower end of the bar. The upper end of each shaft is journaled in a bearing 255 formed in the lower portion of a gear housing 256 (see also Fig. 6). Two of the housings are secured to the under side of the rail 243 and two to the rail 245 and also to the guide bars 246.

Within each of the housings 256, a bevel gear 257 is keyed to the upper end of its threaded shaft 253. At the rear the bevel gears 257 mesh with bevel gears 258 keyed to a rear vertical adjustment shaft 261 and at the front there is the same gearing but the gears 258 are mounted on a front vertical adjustment shaft 262. The rear shaft 261 is journaled in bearings 263 formed in the two housings 256 secured to the rear rail 243 and also in bearings 264 in a gear housing 265 formed in the rear rail 243. The front vertical adjustment shaft 262 is journaled in a similar manner in the front rail 245, there being two other housings 256 and another gear housing 265 for this purpose.

End portions of the front and rear adjustment shafts 262, 261 where they extend into the housings 265 carry spiral gears 266 (Fig. 6) which mesh with spiral gears 267 keyed to the vertical adjustment shaft 222 which is journaled in the housings 265 and projects outwardly at the front of the machine in the square end 224 as previously described.

Turning of the shaft 222 adjusts simultaneously all of the nozzles vertically and in equal amount to locate them properly relative to the upper blank edges of the particular heights of blank desired. This is a simple adjustment in the rotation of the shaft 222 in the proper direction and amount being transmitted through the spiral gears 266, 267, the shafts 261, 262, bevel gears 257, 258 and thence through the vertical threaded shafts 253 which raise or lower the manifolds by virtue of their threaded connection to the bracket plates 252.

When the acid and water treated blanks reach the end of the treating chamber 171 and pass onto the discharge table 206 (Fig. 5) in their circular transfer, they move between lateral guides 268 secured to brackets 269 mounted on the sub-table 207. As each blank passes between these guides to the table 206, portions of its lower edge ride over circular cam rails 271 formed eccentrically with respect to the center of sprocket shaft 161. These rails are bolted to the bracket 163 and cam the blank radially outwardly of the prongs 122.

When the blank is brought into its horizontal position on the discharge table, it is freed of the conveyor chains 123. This action gently places the blank upon lower conveyor belts 272 (Figs. 5, 7 and 10) which carry it under and in contact with upper conveyor belts 273. Both conveyor belts 272 and 273 are driven from an independent motor 274 which is adjustably mounted on an end wall 275 of the main frame 34. Power from the motor is transmitted through a V-belt 276, which takes over a motor pulley 277 keyed to the motor shaft 278. The belt also passes over an intermediate pulley 281 keyed to an intermediate shaft 282 journaled in a bearing 283 formed in the frame 34.

A sprocket 284 keyed to the intermediate shaft

282 further transmits power through a sprocket chain 285 to an upper sprocket 286 keyed to a lower conveyor belt drive shaft 287 which is journaled in lower bearings 288, 289 (Figs. 10, 14) formed in end brackets 291, 292 mounted upon the sub-table 207. A spur gear 293, keyed to the lower shaft 287 adjacent front lower bearing 288, meshes with another spur gear 294, keyed to an upper conveyor belt drive shaft 295. Shaft 295 is journaled in upper bearings 296, 297 formed, respectively, in the brackets 291, 292. A lower conveyor belt pulley 301 is keyed to a mid-portion of the shaft 287 and an upper conveyor belt pulley 302 is keyed to the upper shaft 295. Pulley 302 is directly above and in alignment with the lower pulley 301 and these pulleys thus are rotated in opposite directions, through the means described, from the motor 274.

The upper conveyor 273 and the lower conveyor 272 each comprise six belts, each lower belt 272 being paired with an upper belt 273 immediately thereabove. All of the paired belts contact each other and move along with their driving sides in engagement when no blanks S are being conveyed between them. The lower belts 272 take over the lower pulley 301 by moving within spaced grooves 303 and also over tightening pulleys 304, 305 (Figs. 5 and 10), similarly grooved. Pulleys 304 and 305 are carried on and are keyed to a shaft 306 journaled in an adjustment block 307 adjustably secured to the table 206 adjacent the feed-in end of the table.

Upper belts 273 (Figs. 7 and 10) take over the drive pulley 302 within spaced grooves 311 and also over tighter pulleys 312, 313 keyed to a shaft 314 journaled in an adjustment block 316 adjustably secured to the feed-in end of an upper conveyor frame 317 which is pivotally mounted upon the upper shaft 295 in bearings 318 formed at the discharge end of the frame.

The upper pulleys 312, 313 are spaced horizontally from the lower pulleys 304, 305. In other words the conveyor belts 272 are longer than belts 273 so that each blank S may be deposited directly upon the lower conveyor by the chain conveyor 123, without touching the upper conveyor belts 273. However, after the blank has moved horizontally a short distance with the lower conveyor belts 272, it is engaged from above by the upper conveyor belts 273. Both belts move at the same velocity so that the blank is held between these paired moving belts for the subsequent drying operations.

Each blank S may still have an objectionable quantity of moisture clinging to its upper and lower lateral margins when the blank is received in the belts 272, 273. Much of this moisture is in the form of globules and a large part of such moisture now is removed by air blasts. Air blast units 326 (Figs. 10 and 20) are provided to direct air at high velocity outwardly along the moist surfaces, blowing the moisture away from the lateral edges of the blank.

The air blast units 326, two in number are disposed, one on each side of the path of the blanks, being bolted to the brackets 269 and to brackets 328 secured to the sub-table 207. A short apron 331 (Fig. 20) forming part of each air blast unit merges toward the outer edges of the sub-table into a blast unit housing 332. The marginal edges of an advancing blank extend into and pass along the aprons 331. Such edges pass under an upper air blast distributing orifice 333 formed in an insert 334 which is securely retained in an upper plate 336 bolted to the hous-

ing 332 and over a similar lower orifice 331 formed in an insert 338 fastened to a lower plate 339 which is secured to the apron 331.

Air under pressure is conducted from any suitable source, not shown, to the orifices 333, 331 through piping 341 threadedly engaged at each discharge end in a plate 342. One such threaded plate is secured on top of the plate 336 over an aperture 343 formed therein and with which the discharge end of the piping is aligned. Air passing through the aperture 343 enters a curved conduit 344 formed in the insert 334 and emerges from the distributing orifice 333 at relatively high velocity, so that it is directed across the top surface of the lateral margin of the blank S passing beneath. In this way the two air blast units blow off moisture from the top surfaces of the two marginal edges of the blanks.

Air delivered by the lower piping 341, similarly passes through an aperture 346 in the plate 339 and through a curved conduit 347 in the insert 338 from which it emerges through the distributing orifice 331 to pass over the lower marginal edge of the blank. The air carrying with it the collected moisture from the upper and lower margins of the blank passes within a confining channel 348 formed in the inserts 334 and 338 in the plates 336, 339, emerging through an aperture 349 cut in the housing 332. Here it enters into a baffle chamber 351.

The stream of mixed air and moisture entering the baffle chamber 351 impinges upon baffle plates 352 formed integrally with the housing 332, whereupon the stream is diverted upwardly and substantially at right angles to the direction at which it enters the baffle chamber 351. This baffling action dislodges most of the moisture from the air stream, such moisture adhering to the baffles 352 or to the walls of the baffle chamber 351 from which it drops by gravity to a horizontal wall 353, also formed integrally with the housing 332 and which is located immediately beneath the baffles 352. This moisture as it collects, drips over the edge of the wall 353 flowing through a slot 354 into a lower water chamber 356 formed in the bottom of the housing 332 from which chamber the water is drained through piping 357 to any suitable place of discharge.

The moisture freed air reaching the upper portions of the baffle chamber, passes through a screen 358 arranged over the upper open end of the baffle chamber 351 and secured to the housing by a flange ring 361 fastened to a flange 362 formed in the top of the housing.

Blanks S passing from the air blast units 326 may still carry some retained or residual moisture adhering to their lateral margins and these areas are next treated as they are conveyed between radiant heaters 365. There are two sets of heaters one on each side. Each heater comprises a projector head 366 (Figs. 10 and 21) secured to a heater casing surrounding a gas heat distributing chamber 367. The heater casings are bolted to the brackets 328 and to similar brackets 368 which are mounted on and secured to the sub-table 207.

Gas or gaseous heat, from any suitable source, is supplied through piping 369 and through valves 370 to each of the distributing chambers 367. The gas is distributed in this manner to the two sets of projectors 366 arranged above and to the two sets below the blank marginal surfaces. The projectors 366 provide adequately intense radiant heat which is directed onto the marginal areas from which the retained moisture

is evaporated as the blanks pass between the rows of projectors.

To prevent burning of the lower and upper belts 272, 273 as they pass the radiant heaters 365, water is circulated through chambers 371 and 372 (Figs. 7, 10 and 21) formed respectively in the table 206 and in the frame 317. The outer wall of the table 206 is projected upwardly to provide a shield 374 (Fig. 21) which extends between the lower belts and the lower radiant heaters 365. In like manner the outer wall of the frame 317 is projected downwardly to provide a shield 374 which extends between the upper belts and the upper radiant heaters 365.

Horizontal adjustment of the lateral guides 268, the air blast units 326 and the radiant heaters 365 may be made to accommodate the particular length of blank being treated, see Fig. 10. This may be effected by loosening bolts 375 which pass through elongated slots cut through the brackets 269, 328 and 368, the bolts in each case being threaded into the sub-table 207. When proper adjustment has been made by sliding the brackets over the table the required amount, the bolts 375 are again tightened securely.

The dried blanks are discharged from the end of the conveyor belts 272, 273 into a stacked sheet retaining device 376 (Figs. 7, 10 and 14). This device comprises stack support members 377, 378 secured to the lower ends of support arms 381, 382 which are keyed to transverse shafts 383, 384 journaled in extension brackets 386, 387, 388, 389 mounted on extension supports 391, 392 secured to the sub-table 207. Each blank emerging from the conveyor belts, passes over lower guides 393 and is stopped against vertical guides 394, then drops by gravity between these guides and downwardly bent portions 396 of the lower guides 393. Such a dropping blank is guided at its ends between guide plates 397 adjustably secured to a crossbar 398 fixed at its ends in the extension brackets 388 and 389.

The blank comes to rest in a horizontal position either upon inwardly bent ledges 399 of the support members 377 or upon a stack of blanks supported on those ledges. The support members 377 rest against the vertical guides 394, 396, their supporting arms 381, 382 being designed so that their centers of gravity lie outside of planes passed perpendicularly through the axes of the shafts 383, 384.

When the operator desires to remove the sheets stacked in this manner, he releases them by actuation of a lever 406 (Figs. 10 and 14) keyed to a longitudinally disposed shaft 407 journaled in the brackets 381, 389. The movement imparted to the lever 406 is communicated to the transverse shafts 383, 384 through levers 411, 412 keyed to the shaft 407 and engaging at their free ends rollers 413, 414 pivotally secured to the free ends of other levers 416, 417 keyed to the transverse shafts 383, 384. The shaft support arms 381, 382 keyed to the transverse shafts are thus rocked and the support ledges 399 of the support members 377 swing outwardly and away from their supporting positions under the stack. Thus released, the stack drops by gravity onto a platform 421 (see also Fig. 7) of a truck 422 adapted to be positioned directly beneath the stack retaining device.

The released stack of sheets falls to the truck, being guided by the end guides 397. Truck guide members 423 secured to the platform 421 also assist in this discharge. The guide members 423

are fastened to a truck frame 424 and the frame is supported on four wheels 425 rotatably mounted in the frame and resting in guideways 426 which are formed in rails 427 bolted to an extension support 428 which in turn is secured to the end wall 215 of the base 34. The truck 422 may be pushed in or out of blank receiving position, being retained normally in alignment with and under the stacking device. An adjustable stop 431 (Fig. 7) attached to the end of the sub-table 207 provides a stop against which the truck abuts.

It is retained in this position by a latch 432 carried on the truck which engages a hook member 433 secured to a transverse web 434 of the extension support 428. Latch 432 is formed in the free end of a bell crank lever handle 436 (see also Fig. 10) which is pivotally mounted on a pin 437 fixed in the truck frame 424. The latch is urged into locking position by a spring 438 interposed between the latch and the truck frame, as viewed in Fig. 7. To withdraw the truck from under the stacking device, the operator grasps a handle grip 439 at the outer extension of the bell crank lever 436 and pulls the truck forward, the latch moving about the pin 437 in a clockwise direction which releases the hook 433. The truck is moved on the rails 427 until the truck frame 424 engages a pair of stop plates 441 secured to the ends of the rails 427. The outer position is indicated in full lines in Fig. 10 and in dotted lines in Fig. 7.

Adjustment of the stacking device 376 to adapt it to the particular width of the blank S being treated, may be obtained by loosening bolts 442 (Fig. 14) which pass through elongated slots 443, formed in the crossbar 398. These bolts have threaded engagement with the side guides 397. With the bolts loosened, the guides may be moved to their proper positions. When this adjustment is made the bolts are tightened.

Adjustment of the stacking device for the particular length of the blank S is made by the rotation of either a rear hand wheel 444 (Figs. 7, 10 and 14) or a front hand wheel 445. Each hand wheel is keyed to one of a pair of shafts 446 journaled in a gear housing 447 which is secured to the front bracket 388 or to the rear bracket 389. The inner end of each shaft 446 has threaded engagement with the bracket 386 or with the bracket 387. When either hand wheel is turned, the rotation of its particular shaft 446 is transmitted to the other shaft 446 through a cross shaft 448 which is journaled in each housing 447 wherein it is geared to each of the shafts 446 by a suitable bevel gear drive. Such a drive is shown at the right hand top corner in Fig. 10 and is designated by the numeral 451. Brackets 388, 389 are slidably mounted on the extension supports 391, 392 and may be drawn toward, or moved away from the fixed brackets 386, 387 simultaneously, in accordance with the rotation of the shafts 446 which threadededly engage in the brackets.

Wiring connections to the several electrical units on the machine are shown in a direct current wiring diagram, Fig. 15 and an alternating current wiring diagram, Fig. 16 and consideration of this phase of the machine will now be had.

Considering first the direct current, wires 455 conduct current from any suitable source, not shown, to a switch 456 which, when closed, permits the current to flow through wires 457, 458 to distributing wires 461, 462, across which several units may be connected in parallel circuits.

As an example of one such control unit there is shown in this diagram a control which relates to actuation of the clutch control electromagnet 51. Current for this unit flows from the wire 461, as long as the switch 456 is closed, passing through a wire 477 which connects to the coils of the magnet. Current from the electromagnet 51 returns to the distributing wire 462 through a wire 478. This energizes the electromagnet 51.

This electromagnet operates as a latch device for connecting parts of the clutch 46 with cam moved elements. The electromagnet is mounted on a bearing bracket 480 (Fig. 3) which is secured to the frame 35. Bracket 480 carries a pivot shaft 481 on which two arms 482 and 483 are mounted. The arm 482 is in front of the shaft 47 and in front of a sliding grooved collar member 484 mounted on the shaft and constituting a sliding part of the clutch 46. The arm 483 is located just in back of the collar member, the upper part of this arm extending higher than the arm 482, as shown in dotted lines in Fig. 3. In the same horizontal plane with the shaft 47, the arms 482 and 483 each carry pins 485 which extend into the groove (designated by the numeral 486) of the collar member 484.

A second bracket 487 also mounted on the frame 35 adjacent the bracket 480 pivotally supports a lever arm 488 which extends vertically alongside and in back of a barrel cam 489 carried on the shaft 47. This lever arm carries a cam roller 490 intermediate its length which extends into and operates with the groove of the barrel cam 489. The top of the lever arm 488 extends to a level above the barrel cam 489 and pivotally connects at 491 with a horizontally disposed latch member 492, the forward or free end of which is shaped as a catch hook 493 which is adapted when the latch member is in a lowered position to engage the top of the arm 483.

The shaft 47 rotating continuously during the operation of the machine oscillates the lever arm 488 back and forth through its cam and roller connection 489 and 490 and carries with it the latch member 492. When the latch member is in raised position. Which is the position illustrated in Fig. 3, its catch hook 493 is above and out of engagement with the upper end of the arm 483. This is the normal position and the clutch 46 is in driving connection with the drive shaft. The electromagnet 51 is the operating element used to raise or lower the latch member 492 and this normal or clutched position exists when the electromagnet 51 is energized and the latch member 492 is raised.

The latch member 492 is connected to the solenoid core of the electromagnet 51 by means of a link 494 and as long as current flows through the magnet the parts are in the position shown in Fig. 3. However when the switch 456 is opened, the magnet 51 becomes deenergized and then a spring inside the magnet lowers the solenoid core and pulling down on the link 494 rocks the latch member 492 downwardly so that its hooked end 493 engages the collar 486. Thereafter when the latch member is drawn back under action of the cam 489 the collar member is separated from the rest of the clutch 46 and the clutch is opened. The shaft 45 and all parts connected therewith thereupon cease operating and the feeding of blanks into the conveyor chains 123 also ceases.

Where stop devices are used the various electric controls may be inserted in this direct current diagram. In other words such circuits would be interposed between the distributing wires 461, 75

462. Since such stop devices may vary according to the needs of operation and since such are not needed for an understanding of the invention, they will not be illustrated or referred to further.

For the alternating phase of electric current, reference should be had to Fig. 16 which shows diagrammatically, three-wire alternating circuits connecting the several driving motors of the machine to a source of power, not shown. These will now be considered in some detail. Wires 511 lead from a suitable source of electric energy and conduct the current to a master service switch 512 which, when closed, permits the current to flow to three distributing wires 513, from which the five motors each derive their power.

The motor for the acid or deoxidant pump unit 178 will first be considered. Tap wires 514 connect the distributing wires 513 with a switch 516. This switch when closed, permits the current to flow through motor wires 517 leading to distributing wires of a motor 518 which is the motor for the unit 178.

The water pump unit 198 is next in order. For its motor, current may flow through tap wires 521, through a service switch 522 and motor wires 523 to a motor 524 which drives the water pump unit.

The ventilator unit 173 operates in the same manner. For this purpose tap wires 526 connect to a service switch 527 and motor wires 528 conduct current to a motor 531 which drives the ventilator unit.

The main drive motor 50, which rotates the main drive shaft 47 for operation of the conveyors 123 and other main working parts also receives its driving energy from the distributing wires 513. Tap wires 532 are used in this case, these wires leading to a switch 533. Current passing through the switch leads directly into the motor 50 by way of motor wires 534.

The discharge drive motor 274 is the last to be considered. In this case tap wires 536 leading through a switch 537 pass current through motor wires 538 for the discharge motor.

It will be observed by considering these two sets of circuits of Figs. 15 and 16, that the main motors, 50, 274, 518, 524 and 531 may all be stopped by pulling the master switch 512 or may be individually controlled. This permits operating of certain parts of the machine while other operating mechanisms are inactive. The feeding of blanks into the machine for example may be terminated when desired by opening the switch 456 and this will not affect operation of any of the main motors of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for treating metallic sheets to permit soldering or welding thereof, the combination of means for conveying the sheets through the machine, means disposed above the path of said sheets for ejecting downwardly a stream of a liquid deoxidizing medium against localized portions thereof to deoxidize such portions, means thereafter disposed in the path of said sheets for ejecting a liquid washing medium

against said localized portions of the sheets to remove said deoxidizing medium after the deoxidizing operation, and devices for adjustably moving said deoxidizing means and said washing means to change their position relative to the sheets to adapt the machine to the treatment of sheets of different dimensions.

2. In a machine for treating metallic sheets to permit soldering or welding thereof, the combination of means for confining and conveying the sheets through the machine, a nozzle disposed above the path of said sheets for ejecting downwardly a stream of a liquid deoxidizing medium against localized edge portions only thereof to deoxidize such portions, an auxiliary nozzle also disposed above the path of said sheets for ejecting downwardly a stream of a liquid washing medium against said localized edge portions of the sheets to remove said deoxidizing medium after the deoxidizing operation, means disposed further in the path of the sheets for drying the same after the deoxidizing and washing operations, and devices for bodily adjusting said nozzles and said drying means relative to the path of travel of the sheets to position said nozzles and drying means for treatment of the localized edge portions of sheets having different and varying dimensions.

3. In a machine for treating metallic can body blanks to permit soldering or welding of side seam edges thereof, the combination of means for confining and conveying the blanks in vertical position through the machine, a plurality of nozzles disposed in the path of said blanks and arranged on both sides and above the side seam edges thereof for ejecting liquid deoxidizing medium downwardly along the localized edges only to deoxidize the same, a plurality of auxiliary nozzles also disposed in the path of said blanks and also arranged on both sides and above the side seam edges for ejecting liquid washing medium downwardly along the localized edges to remove said deoxidizing medium after the deoxidizing operation, a blotting device for partially removing moisture from the edges of said blanks, means operating with said conveyor for placing said blanks in horizontal position, feeding means for further conveying said blanks while in horizontal position, air blast means operating along the edges of said blanks while so conveyed to blow off moisture therefrom, and means for separating the air and the retained moisture from said air blast.

4. In a machine for treating metallic sheets of black plate and the like to permit soldering or welding thereof, the combination of means for continuously conveying the sheets through the machine, a plurality of nozzles disposed at opposite sides of and above the path of travel of said sheets for directing streams of a liquid deoxidizing medium downwardly against localized edge portions only to deoxidize the same, means for collecting said deoxidizing liquid after flowing over the sheet edges, a pump line for recirculating said collected liquid and for delivering it under pressure to said nozzles, and auxiliary nozzles also disposed in the path of and above said sheets for ejecting streams of water over the deoxidized areas to wash off the same.

5. In a machine for treating can body blanks formed from black plate and the like to permit soldering or welding thereof, the combination of means for continuously conveying the blanks through the machine, a plurality of nozzles disposed at opposite sides of and above the path

of travel of said blanks for directing streams of liquid deoxidizing medium downwardly against localized edge portions only to deoxidize the same, means for supplying said nozzles with the deoxidizing medium under pressure, heating means for maintaining the deoxidizing medium at a desired temperature, auxiliary nozzles also disposed in the path of and above said blanks for ejecting streams of water over the deoxidized areas to wash off the same, and heating means for maintaining the wash water at a desired temperature.

6. In a machine for treating sheets of black plate and the like to permit soldering or welding thereof, the combination of a continuously moving conveyor for feeding the sheets through the machine in a vertical position while confined on the conveyor, a plurality of nozzles disposed in the path of and above said sheets for ejecting streams of a liquid deoxidizing medium downwardly against localized edge portions only thereof to deoxidize the same, a plurality of secondary nozzles later disposed in the path of and above the sheets for ejecting streams of water downwardly against said localized edge portions to remove the deoxidizing medium therefrom, a discharge conveyor for conveying sheets in a horizontal position, means for transferring the sheets from vertical position into horizontal position on to said discharge conveyor, air blast means for blowing moisture from the washed edges of the sheets while they are carried on said discharge conveyor, and radiant heating devices located above and below the edges of the horizontal sheets on the discharge conveyor for evaporating the remaining moisture to dry the treated sheets thoroughly.

7. In a machine for treating sheets of black plate and the like to permit soldering or welding thereof, the combination of a continuously moving conveyor for feeding the sheets through the machine, a plurality of nozzles disposed at opposite sides of and above the path of travel of said sheets for ejecting streams of a liquid deoxidizing medium downwardly against localized edge portions only to deoxidize the same, a plurality of secondary nozzles later disposed on opposite sides of and above the path of travel of the sheets for ejecting streams of water downwardly against said localized edge portions to remove the deoxidizing medium therefrom, means for supplying said deoxidizing medium and said water to the deoxidizing and to the water nozzles respectively, heating means for heating said deoxidizing medium and said water, and thermostatic instrumentalities for controlling said heating means to provide a predetermined temperature of said deoxidizing medium and of said water.

8. In a machine for treating sheets of black plate and the like to permit soldering or welding thereof, the combination of means for conveying the sheets through the machine in spaced vertical position, a discharge nozzle disposed in the path of and above the moving sheets for projecting downwardly a continuous stream of a liquid deoxidizing medium which flows over localized edge portions only of the sheet to deoxidize the same, said nozzle having a restricted orifice at the top where the deoxidizing liquid enters and which leads into a larger passageway in the lower end of said nozzle to make the discharging liquid stream uniform, and an auxiliary nozzle of similar construction also disposed in the path of and above the sheets for projecting

downwardly a continuous stream of water against the deoxidized edge portions of the sheets to remove the deoxidizing medium and prepare the sheets for soldering or welding.

9. In a machine for treating blanks of black plate and the like to permit soldering and welding of side seam edges, the combination of a magazine for holding the blanks in stack formation, means for conveying blanks through the machine, feeding devices for feeding blanks from said magazine to said conveying means, nozzle means disposed in the path of the moving blanks carried by said conveyor for projecting streams of a liquid deoxidizing medium so that the conveyed blanks have their side seam edge portions only subjected to the liquid streams to deoxidize the same, auxiliary nozzle means also disposed in the path of the blanks for ejecting streams of water against the deoxidized edge portions of the blanks to remove the deoxidizing medium, air blast means effective at the washed edges of the blanks for projecting air against both surfaces of the blanks to remove moisture therefrom, and radiant heating devices mounted in the machine on opposite sides of the moving blanks for projecting and radiating heat from opposite directions to further dry the blanks.

10. In a machine for treating metallic sheets to permit soldering or welding thereof, the combination of a sheet conveyor for conveying successive sheets through the machine, feeding devices for feeding sheets to said conveyor, a deoxidizing manifold extending longitudinally of the machine above the path of travel of the sheets, a row of nozzles secured into said manifold and arranged to project a deoxidizing medium from the manifold as continuous streams to contact localized edge portions only of the conveyed sheets to deoxidize the same, a water manifold disposed adjacent said deoxidizing manifold above the path of travel of the sheets, a row of nozzles secured in said water manifold and arranged to project continuous streams of clean water over a greater area relative to the edge portions of the sheets than is covered by said deoxidizing streams to wash residual deoxidizing medium from all portions of said sheets, a stacking device for stacking said deoxidized sheets, and a discharge conveyor for transferring the deoxidized sheets from said sheet conveyor to said stacking device.

11. In a machine for treating sheets of black plate and the like to permit soldering or welding thereof, the combination of a horizontally disposed conveyor for conveying sheets to be treated, means disposed at opposite sides of and above the path of travel of the moving sheets for projecting downwardly in a vertical direction a stream of deoxidizing liquid directed along a side edge portion of a said sheet while the same is carried by said conveyor to deoxidize said edge portion of the sheet, means for washing said deoxidizing medium from said sheet side edge portion after the liquid has performed its function, feeding devices at the entrance end of the machine for successively feeding sheets to said conveyor, sheet stacking instrumentalities located at the discharge end of the machine for stacking the deoxidized sheets, feeding devices for transferring said sheets from said conveyor into stacking position in said stacking instrumentalities, and manually operated unloading mechanism for extracting a stack of treated sheets from said stacking instrumentalities.

12. In a machine for treating sheets of black

plate and the like to permit soldering and welding thereof, the combination of a conveyor for continuously conveying the sheets through the machine, feeding devices for feeding sheets to be treated to said conveying means, nozzle means disposed in the path of the moving sheets for projecting a stream of a liquid deoxidizing medium, to between said sheets and against localized edge portions only thereof to deoxidize the same, an auxiliary nozzle means also disposed in the path of the sheets for ejecting a stream of water against the deoxidized edge portions of the sheets to remove the remaining deoxidizing medium, a motor for operating the machine, a drive shaft continuously rotated by said motor when the latter operates, a clutch member mounted on said drive shaft and providing operating connection between said feeding devices and said drive shaft, and control means for disconnecting said clutch to stop the feeding of sheets to said conveyor while the latter continues to operate from said drive shaft.

13. In a machine for treating metallic blanks to permit soldering or welding side seam areas along opposite edges of the blank, the combination of means for conveying the blanks through the machine in upright position and with the side seam edges at the sides, a deoxidizing manifold located on each side of and above the path of travel of the blanks for receiving a supply of a liquid deoxidizing medium, a row of nozzles secured into the bottom of said manifold and arranged to project said deoxidizing medium in continuous vertically directed streams along said side seam areas of the blanks to deoxidize the same, a water manifold disposed on each side of and above the path of travel of the blanks for receiving a supply of water, water nozzles secured into the bottom of said water manifolds and arranged to project continuous vertically directed streams of water over said deoxidized side seams, and devices for simultaneously moving both of said deoxidizing manifolds laterally and also vertically to adapt the nozzles to the required length and width for the particular blank size, and other devices for adjusting said water manifolds in the same manner.

14. In a machine for treating sheets of black plate and the like to permit soldering or welding thereof, the combination of a magazine for holding a stack of sheets, a horizontal endless chain conveyor for conveying and confining therebetween sheets to be treated, feeding devices for feeding sheets individually from said magazine to said conveyor, means disposed in the path of the moving sheets for projecting deoxidizing liquid along the two vertical edge portions of a said sheet while the same is carried by said conveyor to deoxidize said edge portions, means for washing off the said deoxidizing medium after it has performed its function, a blotting device for partially removing moisture from the edges of said sheets, air blast means effective on the deoxidized edges of the sheets for blowing off more moisture, radiant heating devices located in the path of travel of the sheets for evaporating the remaining moisture on the sheets, a stacking device for the sheets, a discharge conveyor for transferring the deoxidized sheets from said sheet conveyor to said stacking device, and adjusting means for adjusting all of the aforementioned sheet treating parts of the machine to the particular size of sheet being operated on.

CUSTIS S. WOOLFORD.
